UNITED STATES PATENT OFFICE.

ANNIE SHANLEY, OF NEW YORK, N. Y.

DEVICE FOR RENOVATING GARMENTS.

SPECIFICATION forming part of Letters Patent No. 357,791, dated February 15, 1887.

Application filed April 15, 1886. Serial No. 198,963. (No model.)

To all whom it may concern.

Be it known that I, ANNIE SHANLEY, of the city, county, and State of New York, have invented a new and Improved Device for Renovating Velvet Garments, of which the following is a full, clear, and exact description.

The object of my invention is to provide a practical device whereby the sleeves and shoulders of velvet or other plush garments may be renovated or revived by the application of heat without ripping or removing the sleeves from the body of the garment; and the invention consists of the construction, arrangement, and combination of parts, as hereinafter described and claimed.

Reference is to be had to the accompanying drawings, forming a part of this specification, in which similar letters of reference indicate corresponding parts in all the figures.

Figure 1 is a view showing the support or standard having the sleeve-heating shell and heating-core applied thereto. Fig. 2 is a longitudinal sectional elevation of the sleeve-heater and heating-core placed in the shell. Fig. 3 is a transverse sectional view of the same, taken on the line *x x* of Fig. 2. Fig. 4 is a side elevation of a modified form of standard or support; and Fig. 5 is a sectional view of the heating-shell provided with a gas-pipe for heating the shell by gas.

A represents the standard, *B* the heating-shell, *C* the heating-core, and *D* the gas-pipe fitted in the shell for heating the same when the core *C* is not to be used.

The shell *B* is by preference made of cast-iron or other metal, and in slightly-tapered form, and it is slightly curved to fit the sleeve of a garment, and is made full and curved at *a* to fit the shoulder at or a little above the shoulder-seam of the garment; and upon the shell is placed a covering, preferably consisting of a layer, *b*, of asbestos and an outer covering, *c*, of felt or other fabric, so the garment will not be scorched or otherwise injured by heat.

The core *C* is also, by preference, of cast metal shaped to fit the interior of the shell *B*, as shown clearly in Figs. 2 and 3, and at its upper end it is formed in this instance with a neck and ball, *d*, for attaching it by means of the ball-socket *d'* to the standard *A*. This ball-and-socket connection of the heater to the standard enables the heater to be turned to any desired position relative to the standard, and for locking the heater at any posi-

tion at which it may be placed I provide the standard with a set-screw, *f*, arranged to act against the ball, so that by simply turning the screw against the ball the heater will be locked and prevented from turning out of place.

The standard *A* is formed with rounded shoulders *g g*, to fit the shoulders of a garment, and each shoulder *g* is formed with a socket, *d'*, and there will be two heaters, rights and lefts, to fit both sleeves of a garment. The standard shown in Fig. 4 is concaved in front in line with the core *C*, to permit the core to be removed from and replaced in the shell without detaching the shell from the standard, and with this form of standard the shell *B*, instead of the core, will be formed with the ball *d*, so the connection of the heater to the standard will be by the shell, and not by the core, as in Fig. 1.

In use the core *C* will be removed from the shell *B* and heated, and then replaced in the shell, and the whole connected to the standard *A*, and the sleeve of the garment to be renovated will be drawn upon the heater and properly manipulated to revive the velvet, which can be satisfactorily done without ripping the sleeve or removing it from the body of the garment.

In case the core is not used, the shell *B* will be provided upon its inside with a tube, *D*, preferably perforated, to which gas is supplied by a rubber tube, *K*, so that by turning on the gas and lighting it the shell may thus be heated in a very practical and satisfactory manner; but where gas is not attainable I shall use the core *C*, and to facilitate the withdrawal of the core from the shell I form the shell at its lower end with the eye *e*, and the core with the eye *e'* at its upper or larger end, so that a hook or other device may be inserted in these eyes and the core removed without grasping it or the shell with the hands.

Having thus fully described my invention, what I claim as new, and desire to secure by Letters Patent, is—

The standard *A*, formed with the openings *d'*, and provided with the set-screws *f*, in combination with the sleeve-heater provided with a ball, *d*, substantially as and for the purposes described.

ANNIE SHANLEY.
